US00D897524S

(12) **United States Design Patent** (10) Patent No.: **US D897,524 S**
 Siew et al. (45) Date of Patent: ** Sep. 29, 2020

(54) **COVER FOR A PATIENT INTERFACE**(71) Applicant: **Fisher & Paykel Healthcare Limited**,
Auckland (NZ)(72) Inventors: **Silas Sao Jin Siew**, Auckland (NZ);
Wen Dong Huang, Auckland (NZ);
Craig Robert Prentice, Auckland (NZ);
Andrew Paul Maxwell Salmon,
Auckland (NZ)(73) Assignee: **Fisher & Paykel Healthcare Limited**,
Auckland (NZ)(**) Term: **15 Years**(21) Appl. No.: **29/685,339**(22) Filed: **Mar. 27, 2019****Related U.S. Application Data**

(60) Continuation of application No. 29/572,577, filed on Jul. 28, 2016, now Pat. No. Des. 849,235, which is a division of application No. 29/469,114, filed on Oct. 7, 2013, now Pat. No. Des. 762,844, which is a continuation of application No. 29/401,231, filed on Sep. 8, 2011, now Pat. No. Des. 692,554.

Primary Examiner — Lilyana Bekic(74) *Attorney, Agent, or Firm* — Knobbe, Martens, Olson & Bear, LLP(57) **CLAIM**

The ornamental design for a cover for a patient interface, as shown and described.

DESCRIPTION

FIG. 1 is a front perspective view of a cover for a patient interface;

FIG. 2 is a rear perspective view thereof;

FIG. 3 is a bottom elevational view thereof;

FIG. 4 is a top elevational view thereof;

FIG. 5 is a left side elevational view thereof, the right side elevational view being a mirror image of the view of FIG. 5;

FIG. 6 is a front elevational view thereof; and,

FIG. 7 is a rear elevational view thereof.
